US00D551813S

(12) **United States Design Patent** (10) **Patent No.:** **US D551,813 S**
Renner (45) **Date of Patent:** **** Sep. 25, 2007**

(54) **HIGH PRESSURE CLEANING APPARATUS**

(75) Inventor: **Reinhard Renner**, Esslingen (DE)

(73) Assignee: **Alfred Kaercher GmbH & Co. KG**, Winnenden (DE)

(**) Term: **14 Years**

(21) Appl. No.: **29/263,827**

(22) Filed: **Jul. 28, 2006**

(30) **Foreign Application Priority Data**

Feb. 1, 2006 (EM) 000473574

(51) **LOC (8) Cl.** **15-05**

(52) **U.S. Cl.** **D32/15**

(58) **Field of Classification Search** D32/1, D32/15, 16, 25, 31, 21, 22; 15/3, 323, 403; 134/200, 103.2, 199, 201; 239/146-158

See application file for complete search history.

(57) **CLAIM**

The ornamental design for a high pressure cleaning apparatus, as shown and described.

DESCRIPTION

FIG. 1 is a front elevational view of the high pressure cleaning apparatus showing my new design;

FIG. 2 is a left side elevational view of the design;

FIG. 3 is a right side elevational view of the design;

FIG. 4 is a rear elevational view of the design;

FIG. 5 is a top plan view of the design; and,

FIG. 6 is a bottom plan view of the design.
